FLUID PUMPING AND CONTROLLING MEANS

Donald Wilfred Sessions, Mill Hill, London, England

Application August 20, 1938, Serial No. 226,005
In Great Britain October 6, 1937

13 Claims. (Cl. 103—171)

This invention relates to fluid pumping and controlling means (hereinafter referred to by the term "pump") and especially, although not essentially, to pumps for supplying liquid under pressure into lifting jacks permanently attached to a motor vehicle.

According to the invention the pump comprises a reciprocable double acting horizontal piston in a cylinder supplying pressure through a valve-controlled pressure chamber to lifting jacks or other means, wherein a vertical bore communicates directly at its upper end with the pressure chamber and is associated with a non-return ball valve and each end of the cylinder 10 communicates directly with the lower end of a single straight inwardly and upwardly inclined bore, the upper end of which runs directly into said vertical bore or directly into a horizontal bore leading direct into the vertical bore.

In order that these and other features (defined in the appended claims) of the invention may be more easily understood, a constructional form thereof will now be described by way of example with reference to the accompanying drawings, wherein:

Figure 1 is a top plan view of a pump made in accordance with the invention;

Figures 2, 3, and 4 are vertical sectional views on the planes 2—2, 3—3, and 4—4, respectively, indicated on Figure 1;

Figure 5 is a rear elevational view of the pump with a cover removed; and

Figure 6 is a fragmentary sectional view on the plane 6—6 indicated in Figure 2.

The pump body 10 has a cap 11 on one side closing a chamber 12 into which fluid enters from a supply pipe which is attached to the bottom of the cap at 13. The cap also carries a cylindrical gauze filter 14 that has a ring 15 on its lower end fitting frictionally into the inlet hole 13 in the cap. The middle part of a double acting horizontal pump piston 18 and its operating lever 19 are housed in the chamber 12. The lever 19 is mounted at its lower end on a rocking spindle 20 which is horizontal and transverse to the pump piston and extends out of the pump body on the opposite side to the cap and carries an operating lever 21. The upper rounded end of the lever 19 engages in an opening in the piston. The ends of the piston engage in cylinders (which may be regarded as a single cylinder) formed by a common bore 22 in the pump body that is broken by the said chamber. The ends of the cylinder bore are closed by screwed plugs 23, 24. The pump body is cast

with stops 80, 81 in its interior to limit the movements of the lever 19, thereby preventing the ends of the piston 18 from striking the plugs 23, 24 at full stroke. Ports 25, 26 lead from the chamber 12 into the cylinders and these ports are alternately uncovered to admit fluid and then closed by the piston which continues its movement and forces fluid out of the outer ends of the cylinders through inwardly and upwardly inclined bores 29, 30 into horizontal bores 31, 32 located above the piston and parallel to the rocking spindle. The inclined bores are formed by drilling through the open ends of the bore 22. The horizontal bores have their outer ends opening into the chamber 12 and these ends are normally closed by walls 33 held by opposite ends of a plate spring 35 held at its middle by a return valve 36 to be described later. The inner ends of the horizontal bores are connected by vertical bores or passages 38, 39 with cylindrical wells 20 or pressure chambers 41, 42 formed in a common boss 40 at the top of the pump body. The inclined bores enter the horizontal bores at a position directly below the vertical bores and in fact coincidentally enter the vertical bores. The arrangement of the inclined bores 29, 30, and the vertical bores 38, 39, avoids the necessity for drilling bores through the surfaces of the casting and closing the ends of such bores by plugs. A non-return valve ball 44 seats on the top of each of these vertical passages and the ball is pressed down by a flat ring 45 which engages the ball at one position around its lower surface and is itself pressed down by a helical spring 46 that engages it substantially around the whole of its upper surface. A supplementary non-return ball 47 is also provided in each vertical passage. The wells 41, 42 are closed by threaded blocks or plugs 50, 51, that carry vertical screwdown spindle valves 52, 53, having hand operable knobs 54, 55 on the outer ends and conical valve inner ends. These valves pass slidably through metal guide rings 56 and through rubber packing rings 57 and retaining members 58 which have a radial slot into which the spindle of the valve is engaged whereupon the member 58 engages in a recess in the block 50 (51). These valves are adapted to close vertical ports 60 leading from the fluid spaces in the wells into vertical bores 61 connected at their lower ends with nozzles 62 for connection to the lifting jacks (one to the rear jacks and the other to the front jacks). The outlet bores 62 and the ports 61 which are really continuations of the bores 62, have their axes parallel to the 55

direction of movement of the valve spindle, which considerably simplifies the passage arrangements in the pump. In the bores 62 are cylindrical gauze filters 63 having rings at their lower ends which fit frictionally in said pipes.

5 The filters 14, 63 serve to clean the fluid coming from the jacks and from the reservoir so that dirt is kept out of the pump. These spindle valves, vertical bores, and the pipe ends, are 10 in the same vertical plane to one side of the piston regarded end on. The wells are located adjacent to each other and there is a third well 65 for release formed in the boss 40. The three wells in plan have their centres at the corners 15 of a triangle, the release well being equidistant from the others. Two horizontal holes 66, 67 are drilled so that each connects one of the two outlet wells with the release well so that the outlet wells are in constant communication with 20 each other through the release well. The latter communicates through a vertical port 70 with a horizontal bore 71 leading to the return valve referred to which comprises a sort of bicycle wheel type of valve 73 except that the valve rubber 25 72 is shorter and engaged in an annular groove in the detachable nipple. Fluid leaving this nipple enters the chamber 12 on the inlet side of the pump. The port 70 is controlled by a screwdown valve 75 having a conical valve part 30 76 seating on the upper edge of the bore 70.

The operating lever 21 is short so as to be within the depth of the pump body, and is adapted to receive a tubular extension which is slotted so that it can engage over the valve knobs 54, 35 55, 75, on which are lugs that enter the slots. The same extension is thus used both for the operating handle and for the valve knobs.

Terms such as horizontal and upwardly, are used herein relatively referring to the pump in 40 its normal position, but it should be borne in mind that the pump may be used at an angle to this hypothetical position.

A screwdown valve 76¹ controls an opening to the exterior of the pump for the release of any 45 air or other gas that may accumulate in the chamber 12.

In operation, the valve 75 is closed and one or both of the valves 54, 55 are opened. The handle 21 is then operated which in turn reciprocates the piston 18 thereby drawing fluid in from the inlet 13, 14, 12 and supplying the fluid under pressure through the two inclined bores 29, 30, vertical bores 38, and wells 41, 42, and thence through 60, 61 and 63, into the outlet openings 55 62. When sufficient pressure is built up in the outlet system one of the ball valves 33 leaves its seating and further operation of the pump results in fluid being ejected through the channel 31 or 32 back into the chamber 12.

60 I claim:

1. A pump comprising a casing having a horizontal bore constituting a pump cylinder, a double acting piston therein, a pair of valve controlled pressure chambers positioned above and laterally offset from the pump cylinder and between the ends of said pump cylinder, said casing having a pair of vertical bores one extending downwardly from one pressure chamber and the other extending downwardly from the other pressure chamber, said casing also having a pair of upwardly and laterally inclined rectilinear bores extending from the ends of the pump cylinder up to the lower ends of the vertical bores, said casing also having a fluid inlet adapted to 65 communicate with said pump cylinder, and a 70 non-return valve associated with the upper end of each vertical bore.

2. A pump comprising a casing having a horizontal bore constituting a pump cylinder, a double acting piston therein, a pair of valve controlled pressure chambers positioned above and laterally offset from the pump cylinder and between the ends of said pump cylinder, said casing having a pair of vertical bores one extending downwardly from one pressure chamber and the other extending downwardly from the other pressure chamber, said casing also having a pair of horizontal bores terminating at the lower ends of the vertical bores and a pair of upwardly and laterally inclined bores extending from the ends 15 of the pump cylinder up to the horizontal bores, said casing also having a fluid inlet adapted to communicate with said pump cylinder, a non-return valve associated with the upper end of each vertical bore and non-return valves associated with the horizontal bores past which fluid from the bores can pass to the said fluid inlet when the pressure of the fluid in said horizontal bores exceeds a predetermined maximum.

3. A pump comprising a casing having a horizontal bore constituting a pump cylinder, a double acting piston therein, a pair of valve controlled pressure chambers positioned above and laterally offset from the pump cylinder and between the ends of said pump cylinder, said casing having a pair of vertical bores one extending downwardly from one pressure chamber and the other extending downwardly from the other pressure chamber, a pressure release chamber, said casing also having a pair of horizontal bores 35 disposed at right angles to the piston axis and extending from the lower ends of the vertical bores to the pressure release chamber and a pair of upwardly and laterally inclined bores extending from the ends of the pump cylinder up to the horizontal bores, said casing also having a fluid inlet adapted to communicate with said pump cylinder, and a non-return valve associated with the upper end of each vertical bore.

4. A pump comprising a casing having a horizontal bore constituting a pump cylinder a double acting piston therein, the ends of said cylinder terminating in bores of enlarged diameter and providing shoulders between the ends of the cylinder and said bore of enlarged diameter, a pair of valve controlled pressure chambers positioned above and laterally offset from the pump cylinder and between the ends of said pump cylinder, said casing having a pair of vertical bores one extending downwardly from one pressure chamber and the other extending downwardly from the other pressure chamber, said casing also having a pair of inclined rectilinear bores extending upwardly and laterally from the faces of said shoulders to the lower ends of the vertical bores, said casing also having a fluid inlet adapted to communicate with said pump cylinder, and a non-return valve associated with the upper end of each vertical bore and plugs closing the ends of said enlarged bores.

5. A pump comprising a casing having a horizontal bore constituting a pump cylinder, a double acting piston therein, a pair of valve controlled pressure chambers positioned above and laterally offset from the pump cylinder and between the ends of said pump cylinder, said casing having a pair of vertical bores one extending downwardly from one pressure chamber and the other extending downwardly from the other pressure chamber, said casing also having a pair of vertical bores one extending downwardly from one pressure chamber and the other extending downwardly from the other pressure chamber, said casing also having a pair of vertical bores one extending 70

- of upwardly and laterally inclined rectilinear bores extending from the ends of the pump cylinder up to the lower ends of the vertical bores, said casing also having a fluid inlet adapted to communicate with said pump cylinder, a non-return valve associated with the upper end of each vertical bore, a horizontal rocking spindle, and a lever mounted on said spindle and extending upwardly from the spindle into operating engagement with the piston for reciprocating the latter.

6. A pump comprising a casing having a horizontal bore constituting a pump cylinder, a double acting piston therein, a pair of valve controlled pressure chambers positioned above and laterally offset from the pump cylinder and between the ends of said pump cylinder, said casing having a pair of vertical bores one extending downwardly from one pressure chamber and the other extending downwardly from the other pressure chamber, said casing also having a pair of upwardly and laterally inclined rectilinear bores extending from the ends of the pump cylinder up to the lower ends of the vertical bores, said casing also having a fluid inlet adapted to communicate with said pump cylinder, and a non-return valve associated with the upper end of each vertical bore, each pressure chamber having an outlet bore and a valve for controlling the outlet, the axis of said bore being parallel to the direction of movement of the valve.

7. A pump comprising a casing having a horizontal bore constituting a pump cylinder, a double acting piston therein, a pair of valve controlled pressure chambers positioned above and laterally offset from the pump cylinder and between the ends of said pump cylinder, said casing having a pair of vertical bores one extending downwardly from one pressure chamber and the other extending downwardly from the other pressure chamber, said casing also having a pair of upwardly and laterally inclined rectilinear bores extending from the ends of the pump cylinder up to the lower ends of the vertical bores, said casing also having a fluid inlet adapted to communicate with said pump cylinder, and a non-return valve associated with the upper end of each vertical bore, said pressure chambers having outlet bores and spindle valves controlling the outlets, said outlet bores being in the same vertical plane as the valve spindles and to one side of the piston axis.

8. A pump comprising a casing having a horizontal bore constituting a pump cylinder, a double acting piston therein, a pair of valve controlled pressure chambers positioned above and laterally offset from the pump cylinder and between the ends of said pump cylinder, said casing having a pair of vertical bores one extending downwardly from one pressure chamber and the other extending downwardly from the other pressure chamber, said casing also having a pair of upwardly and laterally inclined rectilinear bores extending from the ends of the pump cylinder up to the lower ends of the vertical bores, said casing also having a fluid inlet adapted to communicate with said pump cylinder, a non-return valve associated with the upper end of each vertical bore, each pressure chamber having an outlet bore in the lower portion thereof, a screw plug closing the top of each pressure chamber, and a screwdown valve stem carried by each screw plug and provided with a conical part adapted to seat in the upper end of the outlet bore.

9. A pump comprising a casing having a horizontal bore constituting a pump cylinder, a double acting piston therein, a pair of valve controlled pressure chambers positioned above and laterally offset from the pump cylinder and between the ends of said pump cylinder, said casing having a pair of vertical bores one extending downwardly from one pressure chamber and the other extending downwardly from the other pressure chamber, said casing also having a pair of upwardly and laterally inclined rectilinear bores extending from the ends of the pump cylinder up to the lower ends of the vertical bores, said casing also having a fluid inlet adapted to communicate with said pump cylinder, a non-return valve associated with the upper end of each vertical bore, said pressure chambers being connected together and formed in a common boss in the pump casing, and a screw plug closing one end of each pressure chamber.

10. A pump comprising a casing having a horizontal bore constituting a pump cylinder, a double acting piston therein, a pair of valve controlled pressure chambers positioned above and laterally offset from the pump cylinder and between the ends of said pump cylinder, said casing having a pair of vertical bores one extending downwardly from one pressure chamber and the other extending downwardly from the other pressure chamber, said casing also having a pair of upwardly and laterally inclined rectilinear bores extending from the ends of the pump cylinder up to the lower ends of the vertical bores, said casing also having a fluid inlet adapted to communicate with said pump cylinder, a non-return valve associated with the upper end of each vertical bore, a third pressure chamber communicating with said pair of chambers and arranged therewith in triangular formation in a common boss in the casing and adapted to communicate with said fluid inlet, and screw valves controlling the outlets of said chambers.

11. A pump comprising a casing having a horizontal bore constituting a pump cylinder, a double acting piston therein, a pair of valve controlled pressure chambers positioned above and laterally offset from the pump cylinder and between the ends of said pump cylinder, said casing having a pair of vertical bores one extending downwardly from one pressure chamber and the other extending downwardly from the other pressure chamber, said casing also having a pair of upwardly and laterally inclined rectilinear bores extending from the ends of the pump cylinder up to the lower ends of the vertical bores, a non-return valve associated with the upper end of each vertical bore, said pump casing having an inlet chamber adapted to communicate with said pump cylinder and an outlet chamber adapted to communicate with said pressure chambers, and a cylindrical filter in each of said inlet and outlet chambers.

12. A pump comprising a casing having a horizontal bore constituting a pump cylinder, a double acting piston therein, a pair of valve controlled pressure chambers positioned above and laterally offset from the pump cylinder and between the ends of said pump cylinder, said casing having a pair of vertical bores one extending downwardly from one pressure chamber and the other extending downwardly from the other pressure chamber, said casing also having a pair of upwardly and laterally inclined rectilinear bores extending from the ends of the pump cylinder up to the lower ends of the vertical bores, said

5 casing also having a fluid inlet adapted to communicate with said pump cylinder, and a non-return valve associated with the upper end of each vertical bore, said valve comprising a ball, 5 an annular member having one point on its under surface engaging said ball and a coil spring engaging a portion of the upper surface of the annular member extending entirely around the same.

10 13. A pump comprising a casing having a horizontal bore constituting a pump cylinder, a double acting piston therein, a pair of valve controlled pressure chambers positioned above and laterally offset from the pump cylinder and between the ends of said pump cylinder, said casing having a pair of vertical bores one extending 15 downwardly from one pressure chamber and the

other extending downwardly from the other pressure chamber, said casing also having a pair of upwardly and laterally inclined rectilinear bores extending from the ends of the pump cylinder up to the lower ends of the vertical bores, said 5 casing also having a fluid inlet adapted to communicate with said pump cylinder, a non-return valve associated with the upper end of each vertical bore, a horizontal rocking spindle, and a lever mounted on said spindle and extending 10 upwardly from the spindle into operating engagement with the piston for reciprocating the latter, said lever being housed in said casing and stops integral with the casing for limiting the movement of said lever. 15

DONALD WILFRED SESSIONS.
